INVENTOR.
Charles C. Hansen
BY
Herbert K. Oden
HIS ATTORNEY.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

ROTARY DRILL.

Application filed June 25, 1926. Serial No. 118,490.

This invention relates to rotary drills, but more particularly to a feeding mechanism of drills of this type for feeding the drill bit to the work and for removing it therefrom.

The objects of the invention are to insure a uniform feeding pressure to the drill bit and to provide adequate adjusting means for the feeding mechanism.

Other objects of the invention will be in part obvious and in part pointed out hereinafter.

The invention is shown in one of its preferred forms in the drawings, in which

Figure 1 is a front elevation of a drill constructed in accordance with the practice of the invention,

Figure 2 is a sectional elevation taken through Figure 1 on the line 2-2 looking in the direction of the arrows, and

Figure 3 is a top plan view of the drill.

Referring to the drawings, the invention is shown embodied in a drill designated generally by A and having a frame B which may be secured to a supporting structure C in any suitable manner. The frame B is provided with side plates D in which is journaled a shaft E carrying at one end or near one end a sprocket F which may mesh with a suitable driving chain (not shown) leading from a prime mover (not shown). Secured to the shaft E is an intermediate gear G which meshes with a drum gear H keyed or otherwise secured to a drum shaft J journaled in the side plates D. A drum K freely rotatable on the shaft J is provided with a cone L at one end to engage a conical recess O formed in one side of the drum gear H in a well known manner.

Any suitable and well known means may be provided for actuating the cone L of the drum K into engagement with the drum gear H, as for instance, linkage P leading from the shaft J to an actuating lever Q located in a convenient position at the base of the supporting structure C. The actuating means for forcing the cone L into engagement with the drum gear H is preferably of such type that when the lever Q is moved in one direction or the other, the drum will be caused to move longitudinally of the shaft J in a well known manner, either to move

the drum into engagement with the drum gear H or out of engagement therefrom.

Secured pivotally to the front end of the frame B as by means of a pin R is a gate S provided with slots T at its free end for the reception of eye-bolts U whereby the gate S may be clamped securely to the frame B to prevent said gate from swinging about the pin R.

In the present instance, the gate S is provided at its upper and lower ends with arms V and W respectively having bores X into which are fitted bushings Y to form bearings for a driving spindle Z. A wearing sleeve b is inserted in the upper bushing Y to rotate therein and is interlocked slidably with the spindle Z by means of a key c. The lower bushing Y is preferably of sufficient diameter to receive rotatably a hollow extension d of a beveled pinion e through which the spindle Z extends. The sleeve b is also provided with a key c which cooperates slidably with a key slot f formed in the spindle Z to prevent relative rotation between the pinion e and the spindle.

The ends of the spindle Z are preferably of smaller diameter than the spindle to form shoulders g against which are seated collars h. The collars h may be screwed to the spindle as illustrated and serve as seats for anti-friction bearings j of cross heads k arranged on opposite sides of the gate S.

In order that the cross heads k may be held against rotation about the axis of the spindle Z, the rods o are arranged slidably through the gate S on opposite sides of the spindle to extend with their ends through the cross heads and are provided with nuts p whereby the cross heads k and the bearings j are held securely against longitudinal movement with respect to the spindle. The lowermost end of the spindle Z in this instance is screw threaded as at q to receive a correspondingly screw threaded chuck r 95 having chuck jaws s for securing a hollow core bit t to the spindle Z.

Suitable and novel means are provided for actuating the spindle Z in the direction of its longitudinal axis for feeding the core bit t into the work or for retracting it therefrom. To this end chains u are ar-

ranged on opposite sides of the spindle Z and are suitably secured at their lower ends to the lower cross head k by means of bolts or pins v and at their upper ends are provided with threaded bolts w which extend through the upper cross head k. Nuts x are screwed on bolts w for supporting the upper ends of the chains and for regulating the tension of the chains u.

10 Secured to a shaft y journaled in the gate S are a pair of sprockets z which mesh with the chains u. The shaft y, and consequently the sprockets z, are preferably off-set from the longitudinal axis of the spindle Z and thus also with respect to the ends of the chains. In order that the chains u may engage a plurality of teeth of the sprockets z, idler sprockets 2 are arranged above and below the sprockets z and between the axes 15 of the shaft y and the spindle Z, said idler sprockets 2 being freely rotatable about suitable shafts 3 journaled in the gate S at their outer ends, and at their inner ends in the arms V.

20 Suitable means are provided for manually rotating the sprockets z to actuate the spindle Z in the direction of its longitudinal axis, either for feeding the core bit t into the work or for retracting it therefrom.

25 To this end a worm gear 4 is mounted freely rotatable on the shaft y and meshes with a worm 5 supported by a bearing 6. The worm 5 is preferably provided with an integral shaft 7, the outer end 8 of which is of hexagonal form to receive a ratchet 9 whereby the worm 5 may be rotated. In the present instance, the ratchet 9 carries a handle 10 and is preferably of the reversible type, so that when the handle 10 lies in one 30 position, as for instance in the position illustrated in the drawing, a downward pull of the handle 10 will rotate the worm 5 in the direction for feeding the spindle Z downwardly. The handle 10 and the ratchet 9 35 may be turned through an arc of 180° to occupy a position on the other side of the worm 5 corresponding to the position illustrated. If desired, a counter-weight 11 may be secured to the handle 10 near its 40 outer end so that in the operation of the device the operator will merely have to raise the handle 10 and thereafter may release said handle since the weight of the counter-weight 11 will be sufficient to rotate the 45 sprockets z for actuating the spindle Z in an endwise direction.

To the end that the manually operable feeding mechanism of the drill may be quickly released in case it be desired to raise 50 the spindle Z by means other than the ratchet 9, a clutch collar 12 carried by the shaft y and normally engaging a clutch jaw 13 of the worm gear 4 may be moved out of engagement with said clutch jaw and the 55 shaft y will then be free to rotate in the

worm gear 4. During the normal operation of the drill the clutch collar 12 will be held in engagement with the clutch jaw 13 by means of a spring 14 seated at one end against the clutch collar and at its other end 70 against a collar 15 at the end of the shaft y.

In the present instance, the rotary movement of the shaft E is transmitted through a counter-shaft 16 for rotating the spindle Z. The shaft 16 is rotatable in the frame B 75 and carries a pinion 17 meshing with an intermediate gear 18 keyed to the shaft E. To the opposite end of the shaft 16 is secured a beveled gear 19 to mesh with a beveled pinion 20 having a hollow extension 21 80 rotatable in a bearing 22 supported by the frame B. The pinion 20 in this instance is held against longitudinal movement with respect to the bearing 22 by the gear 19 and is bored to receive slidably a shaft 23 85 carrying at its front end a beveled gear 24 which meshes with the beveled pinion e in the gate S. The pinion 20 may be secured to the shaft 23 against relative rotative movement in any suitable manner, but such means preferably permit of relative longitudinal movement between the shaft 23 and the pinion 20. In order to accomplish this purpose in the present instance, a key 25 is secured to the pinion 20 to engage a long 90 key slot 26 in the shaft 23.

To the end that the beveled gear 24 may be quickly removed or drawn out of mesh with the pinion e the forward end of the shaft 23 is provided with a slide bearing 100 27 supported in a cylindrical housing 28 of the frame B. The bearing 27 is preferably held against relative rotative movement with respect to the housing 28 by keys 29. The forward portion, or end, of the bearing 27 is 105 preferably reduced somewhat to form an annular shoulder 30 which may abut an inwardly extending flange 31 of the cylindrical housing 28 for limiting the forward movement of the bearing 27. In this way the gear 24 will be prevented from meshing too tightly with the pinion e. The shaft 23 and the bearing 27 are preferably held against relative longitudinal movement by a collar 32 formed on the shaft 23 to abut the rearward end of the bearing 27. A screw 33 110 screwed in the front end of the shaft 23 serves to clamp the gear 24 and the bearing 27 securely on the shaft.

Convenient means is provided for actuating the shaft 23 together with the parts secured thereto in the direction of their longitudinal axes. To this end an anti-friction bearing 34 is secured to the rearward end of the shaft 23 and is seated in a hollow sleeve 35 to provide for free relative rotative movement between the shaft 23 and the sleeve 35 during the normal operation of the drill. The rearward end of the sleeve 35 in this instance is screw threaded to cooperate 115

with the feed screw 36 anchored in the frame B and having a suitable crank 37 at its rearward end whereby the screw 36 may be manipulated.

5 By means of the present invention, I have greatly simplified the construction of drills of this character and have increased the drilling efficiency of such drills considerably. This is due chiefly to the simplified construction and method of manipulation of the feeding mechanism. Owing to the manner of anchoring the ends of the chains *u* and to the provision of means for adjusting the tension of said chains, a uniform, efficient 10 and readily controlled feeding pressure may be at all times obtained. Further advantages of the present invention over other well known devices of this character are that the drive shaft 23 together with the driving 15 gear 24, may be removed entirely out of line of the drill hole and, due to the slideable bearing 27, the shaft 23 is at all times well supported near its outer end. This feature tends to lengthen the life of the drill and 20 at the same time permits the removal of all parts which might act as an obstruction during the operation of inserting casings into the drill hole, thus eliminating the necessity 25 of removing the entire drilling mechanism

from the vicinity of the drill hole to permit 30 the insertion of such casings.

I claim:

1. In a rotary drill, the combination with a frame, a gate pivoted thereon, and a drill spindle rotatable in the gate, of a drive shaft, 35 a gear on the drive shaft to rotate the spindle, a bearing for the drive shaft slideable in the frame and keyed thereto, and means associated with the drive shaft for actuating the drive shaft and the bearing in the direction of their longitudinal axes to withdraw the drive shaft gear within the frame.

2. In a rotary drill, the combination with a frame, a gate pivoted on the frame, and a drill spindle rotatable in the gate, of a drive 45 shaft supported by the frame, a gear on the drive shaft for rotating the spindle, a bearing for one end of the shaft slideable in the frame, a sleeve rotatable on the other end of the shaft, and a screw in the frame to co-operate with the sleeve for actuating the drive shaft and the bearing in the direction of their longitudinal axes to withdraw the gear within the frame.

In testimony whereof I have signed this 55 specification.

CHARLES C. HANSEN.
